J. R. FLEMING.
CAR AXLE JOURNAL BOX AND SUPPORT THEREFOR.
APPLICATION FILED AUG. 12, 1916.

1,241,365.

Patented Sept. 25, 1917.

UNITED STATES PATENT OFFICE.

JAMES R. FLEMING, OF SCRANTON, PENNSYLVANIA.

CAR-AXLE JOURNAL-BOX AND SUPPORT THEREFOR.

1,241,365.

Specification of Letters Patent. Patented Sept. 25, 1917.

Application filed August 12, 1916. Serial No. 114,614.

To all whom it may concern:

Be it known that I, JAMES R. FLEMING, a citizen of the United States, and a resident of Scranton, in the county of Lackawanna 5 and State of Pennsylvania, have invented a new and Improved Car-Axle Journal-Box and Support Therefor, of which the following is a full, clear, and exact description.

Among the principal objects which the 10 present invention has in view are: to provide means for quickly removing a journal box from service; to provide a box of the character mentioned which may be reversed to compensate for service wear; to provide 15 means for readily lubricating roller bearings when employed in said boxes; to maintain said boxes and axles connecting the same in alinement perpendicular to the track bed over which said wheels are operated; 20 and to reduce the wear on said boxes.

Drawings.

Figure 1 is a section elevation showing the inner side of a journal box and mounting therefor constructed and arranged in accordance with the present invention, the axle, part of the cover plate, and adjacent portion of the box being cut away to show the interior construction and arrangement 30 thereof;

Fig. 2 is a horizontal section taken as on the line 2—2 in Fig. 1;

Fig. 3 is a vertical section, the section being taken as on the line 3—3 in Fig. 2;

Fig. 4 is a vertical section showing a modified form of the invention;

Fig. 5 is a vertical section showing a further modification of a structure embodying the invention.

40 Description.

As shown in the drawings, journal boxes when constructed and arranged in accordance with the present invention, have a 45 barrel-like body 10. Extended from the upper surface thereof and centrally disposed is a wearing pad 11, and extending from the center of the pad 11, is a centering dowel 12. The dowel 12, as seen best 50 in Fig. 3 of the drawings, rests in an orifice 13 provided therefor in the pillar plate 14. The weight of the car and the sills 15 thereof, are directly supported by the pillar plate 14 and the pad 11.

55 Journal boxes of the character herein disclosed are peculiarly adapted for use on

mining cars. The wheels 16 of these cars have hubs 17, which are mounted rotatively on the axles 18. The axles 18 have journal sections 19 that rest in the boxes having 60 the bodies 10, and in supported relation to the rollers 27 mounted therein.

A variation in the arrangement of the track beds requires the use of what are known in the trade as "inside wheels," 65 while other arrangements require the use of what are known as "outside wheels." The inside wheels are those where the same are disposed in service inside of the sills 15 and the pillar plates 14 mounted thereon. The outside wheels are those disposed 70 outside of said sills and pillar plates.

In all instances the journal boxes are situated directly below said sills and plates. From this it is obvious that when the axles 75 18 are provided with outside wheels, said axles must extend through both end walls of the journal boxes. With this end in view, the boxes are constructed with an integral end 21 having an orifice therein, and 80 a felt packing 22 annularly disposed about said orifice in wiping contact with the axle 18 to prevent seepage of oil from the boxes.

The opposite end of the boxes is closed by a removable plate 23. The plate 23 is 85 provided with a packing 22 similar to that above described. The plate 23 is held in service relation to the body 10 by bolts 24, the said plate being provided with radially-extended lugs 25 fitting the lugs 90 26 provided on the body 10. This construction renders it possible at any time to replace the plates 23 and thus compensate for wear when the same are subjected to abrasion by the hubs 17 of the wheels 16. 95

The box bodies are provided with suspension lugs 27. The lugs 27 are disposable between and pierced to correspond with bolt-holes provided in the lugs 28 dependent from the pillar plate 14. Through the 100 perforations in the lugs 27 and 28 are extended the bolts 29. The orifices 30 in the lugs 27 for the bolts 29, are purposely enlarged to permit a certain amount of movement of the boxes and the lugs 27 thereof 105 in service.

When boxes are thus mounted in service, it is evident that when through accident or otherwise it becomes necessary to remove or reverse a box, this may be accomplished 110 by lifting the body of the car until the dowel 12 is free of the orifice 13 in the plate

14, the bolts 29 having been previously removed from engagement with the lugs 27 and 28. It is obvious that the elevation of a car to permit this is slight.

- 5 It is obvious that this arrangement effects a great saving in time when performing this operation, for the reason that in former constructions, it has been necessary to remove the plate 14 or parts connected thereto by 10 means of bolts which have extended upward through the sills 15. If the car requiring repair happened to be filled, the annoyance and loss of time necessary to the change, is obvious for the reason that the car would 15 have to be emptied prior to removing the bolts that retained the boxes in position.

The pillar plate 14 is provided at the outer side with a standing liner flange 31. The flange 31 is partially cut away to form 20 an opening 32, whereby provision is made for delivering oil to the passages 33, and by means of said passages to the roller casting of the bearings. The passages 33 deliver oil to channels 34, which channels converge 25 at the center of the boxes for delivery to a main channel 35 extending under the lower half of the boxes and at the center thereof.

It is obvious that whatever oil is poured 30 in the passages 33, will flow to the lower portion of the box bodies 10.

If the roller bearings are provided with the wearing casing 36, as shown in the drawings, this casing is preferably furnished 35 with perforations in line with the central plane of the boxes through which the oil will pass to the interior where the rollers 37 are mounted.

It will be understood that while the casing 40 36 may be thus provided, this is not essential to the satisfactory working of the oiling system for the reason that the oil after filling the channel 35 at the bottom thereof will overflow and pass by and over 45 the edges of the casing, and thus gain access to the path of the rollers. It is obvious that when oil is deposited on the rollers, it will be distributed thereby to the journal sections 19 of the axles 18, providing a perfect 50 lubrication for the same.

In Fig. 4 of the drawings, a modified form of the invention is disclosed, the modification consisting in providing the box bodies 10 with two removable plates 23. 55 When constructed in this manner, it is obvious that in the event of either of the plates becoming worn by attrition with the hub 17 of the adjacent wheel, the box may be temporarily reversed end for end so that 60 the opposite plate will serve to hold the wheel in line and in service position. Also it will be seen that these plates may be quickly and readily renewed when desired.

In Fig. 5 of the drawings, a further modification is shown, the modification herein

consisting in providing the body 10 with a solid end 38, in the exposed face of which an orifice 39 is formed. Boxes thus constructed are used only in connection with the employment of what is known as "inside 70 wheels", that is as shown in Fig. 5 of the drawings, where the wheel 16 is mounted inside of the car sill 15. In this form of the box, it is found unnecessary to provide the channels 34 and 35, the oil here entering an 75 oil chamber 40 at the outer end of the said box to be distributed therefrom to the rollers 37.

Claims.

80

1. A box as characterized comprising a cylindrical body having a weight-supporting member providing a rocking surface for the weight carried thereby, and a positioning member integrally formed with said supporting member for holding said box in permanent relation to the body of a vehicle to which said box is applied; a pillar plate; and means for detachably securing said box to said plate. 90

2. A box as characterized comprising a cylindrical body having a weight-supporting member providing a rocking surface for the weight carried thereby, and a positioning member integrally formed with said supporting member for holding said box in permanent relation to the body of a vehicle to which said box is applied; a pillar plate; and means for detachably securing said box to said plate, said means embodying lugs on said plate and said box, said lugs being perforated to correspond and to receive a retaining member therethrough. 100

3. A box as characterized comprising a cylindrical body having a weight-supporting member providing a rocking surface for the weight carried thereby, and a positioning member integrally formed with said supporting member for holding said box in permanent relation to the body of a vehicle to which said box is applied; a pillar plate; and means for detachably securing said box to said plate, said means embodying lugs on said plate and said box, said lugs being perforated to correspond 110 and to receive a retaining member therethrough, said perforations being enlarged for permitting a rocking action of said box when in service. 115

4. The combination of a car body having lateral sills; pillar plates mounted under said sills; carrying axles for said car body; wheels on said axles; and journal boxes for said axles, said boxes being reversible end for end and having at each end a wearing plate for receiving the wear of said wheels. 120

5. The combination of a car body having lateral sills; wearing plates mounted under said sills; carrying axles for said car body; 125

130

wheels on said axles; and journal boxes for said axles, said boxes being reversible end for end and having at each end a wearing plate for receiving the wear of said wheels, said boxes being provided with oil channels and pouring openings therefor, said openings being juxtaposed to the ends of said boxes and said wearing plates.

6. A box as characterized comprising a cylindrical body; a pillar plate; and means for detachably securing said box to said plate, said means embodying lugs on said plate and said box, said lugs being perforated to correspond and to receive a retaining member therethrough, said perforations being enlarged for permitting a rocking action of said box when in service.

7. In a box as characterized, the combina-

tion of a cylindrical body providing a rocking surface for the weight thereon; a pillar plate; and means for detachably securing said box to said plate; said means embodying lugs on said plate and on said box, said lugs being perforated for receiving retaining members therethrough.

8. In a box as characterized, the combination of a cylindrical body providing a rocking surface for the weight thereon; a pillar plate; and means for detachably securing said box on said plate, said means embodying lugs on said plate and on said box, said lugs being perforated for receiving retaining members therethrough and enlarged for permitting freedom of movement of said body.

JAMES R. FLEMING.
